BED LEE RAIL MOUNTING

Edward E. Woller, Kenosha, Wis., assignor to Simmons Company, New York, N. Y., a corporation of Delaware

Original application November 13, 1939, Serial No. 303,933. Divided and this application May 20, 1940, Serial No. 336,064

3 Claims. (Cl. 5—331)

This invention relates to an improved arrangement for mounting a lee rail on a bed and the main object of the invention is to provide an inexpensive but effective and efficient arrangement for mounting a lee rail on a bed so that it may be quickly and easily removed or mounted as occasion requires. In general, it is the object of the invention to provide an improved bed lee rail mounting, and other objects and advantages of the invention will be understood by reference to the following specification and accompanying drawing wherein there is illustrated a selected form of the improved arrangement for removably mounting a lee rail on a bed structure.

In the drawing:

Fig. 1 is a perspective illustrating one typical application of lee rails to a bed structure;

Fig. 2 is a longitudinal section through a portion of one of the lee rails illustrated in Fig. 1; and

Fig. 3 is a transverse section through a portion of the bed structure including means for cooperating with a lee rail for removably mounting the same on the bed structure.

This application is a division of co-pending application Serial Number 303,933, which became Patent No. 2,297,602 on Sept. 29, 1942.

In Figure 1 there is illustrated one corner of a stateroom or other room wherein there is provided a folding or other upper berth 5, the same comprising a suitable outer frame 6 which supports any desired form of bed bottom structure, mattress, or both. Because of the elevation of the berth 5 from the floor, it is in many cases desirable that an upstanding side frame or lee rail be provided to prevent the occupant from rolling out. In this instance, lee rails 7 and 8 are shown associated with one longitudinal side of the berth and a lee rail 9 is shown associated with one end of the berth.

Where the berth 5 is arranged to be folded from its operative position as shown in full lines in Figure 1 to a folded position against the wall of the room as indicated in broken lines in Figure 1, it is desirable that the lee rails be removed or collapsed so as to reduce the extent to which the bed structure projects from the wall. In this instance, the lee rails are removably mounted so that they may be stored flat in the berth when it is folded or elsewhere if preferred.

Lee rails such as typified by the above described arrangement are employed in other places, for example, on hospital beds, children's beds and in other instances not necessarily embodying an upper or elevated bed structure and it will be un-

derstood that the herein described invention is applicable generally to the mounting of lee rails on beds and that it is not restricted in its application to the illustrated folding berth arrangement.

The lee rails such as typified by the end lee rail 9 may conveniently be made of tubular metal suitably formed and provided with vertically extending end portions 10 and 11. In one of the end portions, i. e., the end portion 11, there is mounted a post member 12, the same depending from the lower end of the lee rail end portion 11 and being rigidly anchored therein in any suitable manner.

15 In the other lee rail end member 10 there is laterally adjustably mounted another post member 13. As best shown in Figure 2, said post member 13 is provided with a stem part 14 of smaller transverse dimension than the corresponding dimension of the hollow end part 10 of the lee rail. Intermediate its ends, the post stem 14 is provided with a socket or recess 15 which receives a helical coil spring 16. The said coil spring projects from the side of said stem part and engages the adjacent inside surface of the hollow lee rail part 10 and is under sufficient compression to yieldingly urge the post and its stem part to one limit of its range of lateral movement as determined by the inside wall portion 17 of the hollow lee rail part 10.

20 The post 13 is anchored against withdrawal from the lee rail part 10 in any suitable manner, in this instance by means of a rivet or the like 18 extending transversely through the lee rail part 10 and through an enlarged opening 19 in the stem 14. Said opening 19 is of such size that the post 13 and its stem 14 may freely move to the full extent permitted by the relatively greater interior dimension of the lee rail part 10 as compared with the stem 14.

25 The bed structure is provided with sockets for receiving the posts 12 and 13, such sockets being conveniently in the form of tubes such as indicated at 20 in Figure 3, the same being suitably mounted in the frame 6 of the bed. In this instance, the frame 6 is illustrated as being formed of upper and lower tubular members 21 and 22, respectively, suitably connected and covered with a sheet metal facing 23. The socket 20 is positioned in the frame by being passed through suitable holes drilled through the upper member 21 and by being seated in the lower member 22 by being passed through a hole drilled in the upper wall portion thereof. The socket tube 20 may be anchored in place by suitable means, for example,

by welding the same to either or both the upper or lower flat portions 21. One such socket is provided for each lee rail post 12 and 13.

The sockets such as 20 are located in the bed frame at points which correspond to the spacing of the lee rail mounting posts 12 and 13. In the positioning of the sockets 20 during production of the bed structures and in the manufacturing of the lee rails, some practical difficulties are experienced in securing exact corresponding spacing between the posts of the lee rail and the sockets of the bed frame.

Inaccuracies in such spacing result in serious difficulties in respect of the mounting of the lee rail on the bed frame and the removal of the lee rail. In the described arrangement, such difficulties are effectively overcome since one of the lee rail posts 13 is laterally adjustable to an extent which is sufficient to permit the post to adjust itself to the exact location and alignment of the socket into which it is to be inserted.

The range of adjustment practically feasible in structures such as above described is ample to overcome the otherwise adverse effect of the normal range of inaccuracy experienced in respect of the relative spacing of the posts and sockets in the practical manufacture of devices of this character. As best shown in Figure 3, the socket forming tube 20 may be permitted to project upwardly above the top surface of the bed frame structure 6 to such an extent as to prevent engagement of the lower ends of the lee rail parts 10 and 11, with the adjacent top surface of the bed side frame. By this means, scratching of the finish of the bed structure by the lee rail is avoided.

Changes in the described structure may be made without departing from the spirit of the invention, the scope of which should be determined by reference to the following claims, the same being construed as broadly as possible consistent with the state of the art.

I claim:

1. In a bed structure, a frame member, a lee rail having a hollow portion, a pair of relatively spaced posts extending from said lee rail, one of said posts having a portion extending into said hollow lee rail portion and laterally movable therein, means for anchoring said laterally movable post to said lee rail, means for resiliently urging said post toward one limit of its lateral movement in said hollow lee rail portion, and said frame having a pair of relatively fixed spaced sockets respectively adapted to receive said posts for removably mounting said lee rail on said frame.

2. In a bed structure, a frame member, a lee rail having a hollow portion, a pair of relatively spaced posts extending from said lee rail, one of said posts having a portion extending into said hollow lee rail portion and laterally movable therein, means for anchoring said laterally movable post to said lee rail, means carried by said post for resiliently urging said post toward one limit of its lateral movement in said hollow lee rail portion, and said frame having a pair of relatively fixed spaced sockets respectively adapted to receive said posts for removably mounting said lee rail on said frame.

3. A lee rail structure of the class described comprising a hollow post part, a post extension having a portion projecting from said hollow post part and a portion extending inwardly into said hollow part, said inwardly extending portion being laterally movable in the hollow post part, means for anchoring said laterally movable post extension against endwise removal from said hollow post part, and means for resiliently holding said post extension in a predetermined position of lateral adjustment relative to the hollow post part.

EDWARD E. WOLLER.
